UNITED STATES PATENT OFFICE.

WILLIAM RAMSING, OF SCHENECTADY, NEW YORK.

DESIGN FOR A TABLE OR MANTEL ORNAMENT.

47,801.

Specification for Design.

Patented Sept. 7, 1915.

Application filed February 23, 1915. Serial No. 10,142. Term of patent 7 years.

To all whom it may concern:

Be it known that I, WILLIAM RAMSING, a citizen of the United States, residing in the city of Schenectady, county of Schenectady, and State of New York, have invented a new, original, and ornamental Design for a Table or Mantel Ornament, of which the following is a specification, reference being had to the accompanying drawing, forming part thereof.

The figure is a perspective of a table or mantel ornament showing my new design.

I claim:

The ornamental design for a table or mantel ornament, as shown.

WILLIAM RAMSING.

Witnesses:

BEULAH CARLE,
FREDERICK W. CAMERON.
